UNITED STATES PATENT OFFICE.

KARL VÖLLER, OF DÜSSELDORF, GERMANY.

GUN.

1,413,076.

Specification of Letters Patent. Patented Apr. 18, 1922.

Application filed June 19, 1914. Serial No. 846,105.

(GRANTED UNDER THE PROVISIONS OF THE ACT OF MARCH 3, 1921, 41 STAT. L., 1313.)

To all whom it may concern:

Be it known that I, KARL VÖLLER, engineer, a subject of the German Emperor, residing at Dusseldorf, 12 Scharnhorststrasse, Germany, have invented certain new and useful Improvements in Guns; and I do hereby declare the following to be a full, clear, and exact description of the invention, such as will enable others skilled in the art 10 to which it appertains to make and use the same.

My invention relates to improvements in guns, and more particularly to guns which are suitable for firing on balloons and other 15 aerial machines. Guns of this class such as are now in use are objectionable in this respect that comparatively much time is required in order to point and traverse the gun at great angles, because for traversing 20 the gun at great angles, it is necessary to move the whole gun carriage over the ground, whereby aiming is interfered with. The object of the invention is to provide a gun and its carriage which are not subject 25 to this objection. With this object in view my invention consists in mounting a pivot gun on a carriage which is provided with two wheels and can be limbered and unlimbered, so that after unlimbering, it is 30 directly in the position for aiming. However, when thus constructing the gun and its carriage the pressure of the trail eye and the length of the gun and the limber are too large. For this reason the preferred form 35 of my invention consists in so constructing the pivot gun that it can be tilted over towards the axis of the wheels, so that the latter take up the main part of the weight.

For the purpose of explaining the invention several examples embodying the same 40 have been shown in the accompanying drawings, in which the same letters of reference have been used in all the views to indicate corresponding parts. In said drawings—

Fig. 1 is a side view of the gun and its carriage,

Fig. 2 is a plan view of Fig. 1,

Fig. 3 is a cross-section taken on the line 3—3 of Fig. 1,

Fig. 4, 5 and 6 are longitudinal sections 50 of a detail showing the same in three different positions,

Fig. 7 is a detail view showing a braking mechanism provided in the gun carriage shown in Fig. 1,

Fig. 8 is a side view of a modification of the invention,

Fig. 9 is a cross-section taken on the line 9—9 of Fig. 8 and

Fig. 10 is a side view showing a further 60 modification of the invention.

Referring to the example illustrated in Figs. 1 to 7, the barrel *d* of the gun is mounted in a cradle *c* provided with trunnions *b* by means of which it has a rocking support 65 on a member *b'* which is pivotally mounted on a bracket or pedestal *a*. The said bracket is mounted on a platform *f* and is adapted to be rocked about a horizontal fulcrum *e* and towards the axle 1 of the wheels. The 70 platform *f* is disposed between the cheeks *g* of the gun carriage, and it is adapted to be broadened by means of two lateral members *h* carrying rockable spurs. When the gun carriage is in limbered up position, the lateral members *h* are folded upwards. At the 75 side of the bracket which is opposite to the fulcrum *e* a claw *k* is secured to or made integral with the bracket *a*, which is adapted to be brought into engagement with an axle 80 1 provided on the carriage and adapted to be operated by means of a lever *m*, so that with the claws in engagement with each other the rocking bracket *a* is locked against rocking movement about its fulcrum *e*. When 85 turned downwards and towards the axle of the wheels of the carriage the bracket *a* is locked by means of two claws *n* engaging complementary claws *o* provided on the cradle of the gun. The claws *n* are slidably 90 mounted on a guide member *p* disposed transversely of the carriage and between the side walls of the same, and for moving the same into and out of locking engagement with the claws *o* a shaft *q* is provided, said 95 shaft having a right and left hand screw engaging in screw threaded bores of the claws *n*. In order that the gun can more easily be tilted downwards or upwards, a power storing mechanism is provided which 100 as shown consists of two telescoping cylindrical sleeves *r* and *s*, the sleeve *s* being jointed to an arm *t* connected with the bracket *a*. Within the sleeves a rod *u* is

guided which is jointed at its outer end to a cross-piece v secured to the side walls of the carriage. The rod u is made integral with a rod w of larger diameter which is guided 5 within the sleeve s . Within the sleeve r a coiled spring x is located which bears with one end on a cap r' screwed to the sleeve r and with its opposite end on a grooved cap y provided on the rod u , which in the position shown in Figure 4 bears on the shoulder provided by the rod w . In Fig. 4 I have 10 shown the parts of the spring mechanism in the positions they occupy when the bracket a is upright. When the latter is being turned downwards the tension of the spring is reduced as the center of gravitation of the bracket a and the parts mounted thereon approaches the position above the fulcrum e of the bracket a . This position of the parts 15 is shown in Fig. 5. The balancing spring is now under no tension whatever and the cap y is in contact with a flange formed on the inner end of the sleeve s . When the center of gravitation moves beyond the position 20 above the fulcrum, the cap y is shifted by the flange z of the sleeve s so as to put the spring under tension. When the bracket a has been completely turned downwards, the parts of the balancing device are in the 25 position shown in Fig. 6.

By turning the bracket a with the gun mounted thereon downwards the weight of the parts is shifted further towards the axle 1 of the wheels, so that the pressure of the 30 trail eye on the limber is comparatively small. In order to be able to reduce the said pressure further and to reduce the aggregate length of the gun carriage and the limber the axle of the wheels is so connected with 35 the gun carriage as to be shiftable relatively thereto. As shown the axle is provided with a square portion 2 by means of which it is guided in slots 3 of the cheeks of the gun carriage. Between the cheeks of the carriage a tube 4 is rotatably mounted on the axle 1, and is provided at opposite ends with 40 pinions 5 engaging in cogs 6 secured to the cheeks of the gun carriage below the slots 3. By means of a lever or a pawl and ratchet 45 mechanism the tube 4 can be rotated so as to shift the axle of the wheels in the slots of the carriage. In order to lock the axle in position, and to take the strain from the 50 gearings, when driving or when firing, 55 blocks are provided which are placed into the slots so as to fill the same.

On the axle 1 a brake is mounted which is adapted to be shifted therewith. The 55 brake mechanism consists of braking rings 8 disposed one in each of the hubs 7 of the wheels and secured to a sleeve 9 embracing the square part of the axle of the wheel. At one part the said rings are open and the 60 open ends are provided with jaws 10. Between the said jaws a pair of cams 12 are

located which are provided on a rock shaft 11 and which are adapted to spread the rings apart and to force the same into braking engagement with the hub 7. For rocking the shaft in the manner described a lever 13 is 70 provided which can be set in braking position relatively to a toothed segment 14.

The trail of the gun carriage is provided at its end with spurs 15 and with a lever 17 carrying the trail eye 16, which lever is 75 rocked upwardly for firing to allow spurs 15 to be rammed into the ground.

The example illustrated in Figs. 8 and 9 is distinguished from the example described with reference to Figs. 1 to 7 in so far as instead of mounting the hubs of the wheels for shifting displacement relatively to the bracket a the said bracket is adapted to be shifted towards and away from the axle of the wheels. It will be understood, that both 80 85 constructions may be provided in the same carriage.

As shown in the said figures, the bracket a' is mounted on a platform b' which is shiftable in longitudinal direction in guide 90 ways formed on the side walls of the trail c' of the carriage. The platform is made in two sections one of which provides a support for the bracket a' and is adapted to be rocked relatively to the other one about 95 the fulcrum g' , so that the gun can be tilted downwards and towards the axle of the wheels in the same way as has been described with reference to Figs. 1 to 7.

To the front part of the platform b' a nut 100 d' is secured which is engaged by a screw-threaded rod e' mounted on the frame of the trail of the carriage and adapted to be rotated by means of a crank f' so as to advance or retract the platform b' with the 105 barrel of the gun mounted thereon.

In the construction shown in Fig. 8 the platform is prevented from being lifted away from the frame of the gun carriage when in firing position by one or more claws 110 h' secured to the frame of the carriage. For driving, the gun is shifted forwards by turning the crank f' and thereupon tilted about its fulcrum g' , until it arrives in the 115 position shown in broken lines.

In the example shown in Fig. 10 it is not necessary to shift the axle of the wheels or the bracket a or a' , the bracket a^2 being connected with its fulcrum through a forwardly projecting arm g^2 , so that when turning the said bracket the center of gravitation of the bracket and the parts carried thereby is brought near the axle of the wheels without providing special shifting means.

The barrel of the gun is mounted on the 120 cradle c^2 which is supported by trunnions b^2 on the upper part of the bracket a^2 . The latter is adapted to be tilted about its fulcrum e^2 towards the axle f^2 of the wheels f .

The bracket a^2 is formed at its bottom 125

with an arm g^2 which projects forward therefrom and at its front end is fulcrumed at e^2 . Therefore when rocking the bracket and the parts mounted thereon forward the center of gravitation of the system is shifted forward and toward the axle of the wheels. In this construction it is not necessary to provide special means for shifting the axle f^2 of the wheels rearwardly or the bracket a^2 forwardly, so that the operation of the gun is comparatively simple, and the gun can more quickly be thrown into action, as is particularly important in guns designed for firing on aerial machines.

15. I claim herein as my invention:

1. A gun carriage having carrying wheels, a gun provided with a support, said support hinged to the carriage in rear of the wheels, and adapted to be swung toward the wheels 20 for positioning the gun over the axle of the

wheels, and means for supporting the gun above the axle of the wheels.

2. The combination of a gun carriage having elongated slots in the sides thereof, an axle slidably mounted in the slots of the carriage and having carrying wheels mounted thereon, a support having a gun mounted thereon pivotally connected to the carriage, said support being adapted to be swung forward for positioning the gun over the 2 axle, and means for moving the axle and wheels longitudinally of the carriage.

In testimony whereof, I have signed this specification in the presence of two subscribing witnesses.

KARL VÖLLER.
